UNITED STATES PATENT OFFICE.

EUGEN BRUNNER, OF AKRON, OHIO, ASSIGNOR TO LUFTSCHIFFBAU ZEPPELIN GESELLSCHAFT MIT BESCHRANKTER HAFTUNG, OF FRIEDRICHSHAFEN, BODENSEE, GERMANY.

AIRSHIP.

Application filed January 19, 1925, Serial No. 3,264, and in Germany February 11, 1924.

My invention relates to aircraft lighter than air, and especially to such airships which have some rigid structure.

When speaking of airships I mean aero-
5 stats, the support of which is chiefly due to the buoyancy caused by a lifting gas, in con-
tradicition to airplanes, supported by the
dynamical action of the air.

The disposable lift of an airship comprises
10 fuel, crew, ballast and paying load as pas-
sengers, mail and freight. The same airship
may be used for long trips carrying only a
few passengers but taking much fuel, while
it may as well serve for shorter trips where
15 less fuel will be necessary but more passen-
gers may be taken. It would be an enormous
additional weight to the airship if rooms for
all paying load that might possible be taken
on shorter trips would be provided in the
20 airship structure from the beginning, and
the weight of such partitions for rooms would
unnecessarily cut down the lift disposable
for paying load on long trips where part of
such arrangement would not be made use of
25 but carried along as dead weight.

Therefore, according to my invention, I
provide for partitions which are not a part of
the original ship structure but which may
be put up if necessary and which may be re-
30 moved again afterwards. Such partitions
may be arranged in any place of the lighter
than air ship, but I prefer to provide for
them in connection with the usual gangway
35 structure of the airship where it is especially
advantageous to have the necessary addi-
tional rooms, as the gangway will naturally
provide for access to them.

Having given a general explanation of my
invention, I now want to point it out in de-
40 tail referring to the drawing in which an ex-
ample embodying my invention is shown.

Fig. 1 is a diagrammatical cross section of
the gangway of an airship to which the par-
titions for an additional room have been
45 fastened (seen in the direction of arrow A
in Fig. 2). Fig. 2 is the corresponding side
elevation in part, and Fig. 3 is the ground
plan corresponding to Fig. 1.

The longitudinal girders of the gangway
50 are designated by the letter *d* and the cross
girders are shown at *g*. The inner edge of
the floor *a* of the additional room is con-
nected with the lower girder *d'* of the gang-
way by means of hinges *b*. Its outer edge is

supported by tension members *c* which are 55
fastened to the upper longitudinal gangway
girder *d''*. These tension members may be
provided with turnbuckles *e* for the purpose
of accurate adjustment. Other tension mem-
bers *c'* are provided for rigidly staying the 60
floor *a* by connecting its outer edge with
girder *d'*. These tension members may be
arranged so as to intersect and they also may
have turnbuckles.

I prefer to have the floor *a* constructed as 65
one undivided rigid structure. The walls *f*
confining the additional room may easily be
put up resting on the floor platform *a* and
will be connected with the same, with each
70 other and possibly with the upper gangway
girder *d''* in any suitable and well-known
manner.

It is to be seen that the installation of floor
80 *a* as well as its removal will take only a very
short time. For many purposes it will be 75
satisfactory to have only floor *a* put up, with-
out walls *f*, for example, if additional space
for baggage or mail only is wanted. But it
will also be easy to add the walls *f* in case
passenger cabins or quarters for the crew
should be wanting. For longer trips, fuel
tanks, for example, may be substituted for the
collapsible structure. Occasionally it may
also be useful to take the parts of the col-
lapsible structure with the ship, but in folded 85
up state, so as to be able to put the structure
up while on the trip if so desired.

I do not intend to limit myself to the de-
tails described or shown in the drawing, as
many variations will occur to those skilled 90
in the art.

What I claim is:

1. In an airship, a rigid structure, a floor
platform, means for detachably connecting
one edge of said platform to said structure 95
and tension members at the other edge of
said platform adapted to detachably support
same from said structure.

2. In an airship, a rigid structure, a floor
platform, means for detachably connecting 100
one edge of said platform to said structure,
and tension members at the other edge of
said platform adapted to detachably support
same from said structure and to rigidly se-
cure same in relation to said structure. 105

In testimony whereof I affix my signature.

EUGEN BRUNNER.
